United States Patent Office

Des. 228,986
Patented Nov. 6, 1973

228,986

BENCH

Farid A. Iskander, Brooklyn, N.Y., assignor to Herman
Miller, Inc., Zeeland, Mich.

Original design application July 9, 1969, Ser. No. 18,126,
now Patent No. 222,052. Divided and this application
June 23, 1970, Ser. No. 23,630

Term of patent 14 years

Int. Cl. D6—07

U.S. Cl. D6—58

FIG. 1.

FIG. 2.

FIG. 4.

FIG. 3.

FIG. 1 is a perspective view of a bench according to the invention;

FIG. 2 is a front elevational view of the bench, the rear view being a mirror image of the front;

FIG. 3 is an elevational view of one of the two identical sides; and

FIG. 4 is a plan view of the bench.

This application is a divisional of my earlier filed design patent application Ser. No. D-18,126 filed July 9, 1969 and now Design Patent No. D-222,052.

I claim:

The ornamental design for a bench, as shown and described.
